US00D837662S

(12) **United States Design Patent** (10) Patent No.: **US D837,662 S**
 Bonati (45) Date of Patent: ** Jan. 8, 2019

(54) **WATCH BRACELET**

(71) Applicant: **OFFICINE PANERAI AG**,
 Steinhausen (CH)

(72) Inventor: **Angelo Bonati**, Milan (IT)

(73) Assignee: **OFFICINE PANERAI AG**,
 Steinhausen (CH)

(**) Term: **15 Years**

(21) Appl. No.: **35/502,955**

(22) Filed: **Nov. 10, 2016**

(80) **Hague Agreement Data**

Int. Filing Date: **Nov. 10, 2016**

Int. Reg. No.: **DM/093647**

Int. Reg. Date: **Nov. 10, 2016**

Int. Reg. Pub. Date: **May 12, 2017**

(51) **LOC (11) Cl.** **10-02**

(52) **U.S. Cl.**

USPC **D10/32; D11/3**

(58) **Field of Classification Search**

USPC D10/30, 31, 32, 38; D11/2-10, 19-33,
 D11/79-85

CPC .. A44C 5/00; A44C 5/061; A44C 5/02; A44C
 5/2071; A44C 5/0084

See application file for complete search history.
